[57] ABSTRACT

Illegal or unauthorized ingress or egress from a building through an aperture such as a window is prevented by a telescopically adjustable safety and security device mounted in the aperture which may be readily pivoted out of the way when it is not required.

5 Claims, 1 Drawing Figure

PATENTED JUN 12 1973

3,738,062

SECURITY AND SAFETY DEVICE FOR APERTURES IN BUILDINGS

BACKGROUND OF THE INVENTION

Through the years various devices have been provided for installation, primarily in windows, which prevent occupants inside the room from falling through an open window, particularly young children or elderly and infirm adults, and more recently in importance, these devices are also designed to prevent access into the room through the window aperture by unauthorized persons embarked on nefarious missions. Devices of this type are also employed as detention means in hospitals, penal institutions, and the like.

STATEMENT OF THE INVENTION

It is the principal object of this invention to provide an improved device of the aforesaid type which may be installed in apertures of buildings, such as windows and doors.

It is a further object to provide such a device which is readily adjustable in the transverse direction and which therefore may be installed in apertures of various widths.

It is still a further object of this invention to provide such a device which may be swung out of its normal position of juxtaposition to the window or door and facilitate the cleaning of the same or permit entrance and/or egress of articles or individuals if such is desired from time to time.

The foregoing objects are accomplished by my invention, which comprises in combination with a window or door aperture:

1. a vertically disposed right-angle shaped rigid member securely fastened to a vertical jamb of said aperture, said member having at least one horizontally disposed support shelf;
2. a pair of rigid members in telescopic relationship to one another pivotally mounted on said support shelf of said vertical member and restrained from movement in the vertical direction when said telescopic members are in the locked position in said aperture, said telescopic members comprising a first member consisting of two hollow parallel spaced horizontal arms connected by a multiple number of vertically disposed grid arms sufficient in number to bar ready passage through said aperture, and a second member which telescopes into said first member consisting of two similarly spaced and parallel horizontal arms connected together at the far end with a vertical grid arm having an aperture therein;
3. a second vertically disposed rigid member securely fastened to the other vertical jamb of said aperture and having a horizontally disposed element which engages said aperture in said vertical grid arm of said telescopic member when said telescopic member is opened to the full width of said aperture;
4. and locking means for securing said engaged members.

DESCRIPTION OF THE DRAWING

The single FIGURE is an elevation of a window opening with the improved safety and security device of the invention mounted therein.

DESCRIPTION OF THE PREFERRED EMBODIMENTS

The subject invention comprises in combination with an aperture 10 such as a window, having two vertical and parallel disposed jambs 12 and 14, a safety and security device 13. In the preferred embodiment, the device 13 comprises in part a right-angle shaped rigid vertical member 16 securely fastened to jamb 12 suitably by means of screws 18 and a second rigid vertical member 20 securely fastened to jamb 14 also by means of screws 18. Said rigid vertical member 20 is provided with a horizontally disposed element 22 preferably integral to member 20 and which is provided with a circular opening 24 at its outer end for a purpose which will be explained below. Pivots mounted on said vertical member 16 is a horizontally disposed member 15 consisting of two hollow horizontal and spaced parallel arms 26 and 28 joined together by a plurality of vertically disposed grid arms 30 and 32. The mounting may suitably be accomplished as shown in the drawing by providing vertical member 16 with support and restraining shelves 34, 34' and 36, 36', said shelves 34' and 36' having openings 38 and 40 into which pivot pins 42 and 44 mounted on said horizontal members 26 and 28 are disposed. Suitably, the shelves are dimensionally related one to another so that the parallel arms 26 and 28 with the pins 42 and 44 secured thereto may be slid into position by being approached at right angles so that the pins 40 and 42 will drop into the openings 38 and 40 but such that the parallel arms 26 and 28 can not be moved in the vertical direction when the arms are across the aperture 10 in the closed position. Into horizontally disposed member 15 a telescoping member 17 is disposed comprising two horizontally spaced arms 46 and 48 secured together by a vertical grid arm 50 having an aperture 54 therein. Aperture 54 is of such a size and location to receive member 22 when the telescoping member 17 is extended to the proper width to close the window aperture 10.

The vertical members 16 and 20 secured to the window or door jamb may be made of any suitable rigid structural material, and sand-cast aluminum has been found to be particularly satisfactory. Similarly while any rigid structural material which permits the requisite telescoping action is suitable for members 15 and 17 square cast aluminum tubing is highly satisfactory.

Once the member 15 is mounted in the window or door aperture, as aforesaid, and the telescoping member 17 is opened to the full width of the aperture, a key lock 56 may be passed through the opening 54 to secure the safety and security device in position.

As will be appreciated from the foregoing description, once the device has been mounted in a window or door aperture, it may readily be pivoted away from the window, for example, for cleaning the same by unsecuring the locking means, sliding the telescoping member in to disengage the engaged pivotal member from the window jamb structure and then swinging the device open like a door. It will also be appreciated that the means for securing the pivotal member of the safety and security device to the window jamb structure may be other than a key lock such as a combination lock, etc. Finally, depending upon the primary purpose of the device in any given situation, the device may be mounted on the inside or the outside of a glass window pane in a given window frame.

I claim:

1. A safety and security device which comprises in combination with a window or door aperture:
  - a. a vertically disposed right-angle shaped rigid member securely fastened to a vertical jamb of said aperture, said member having a pair of horizontally disposed support shelves at both its uppermost end and its lowermost end;
  - b. a pair of rigid members in telescopic relationship to one another pivotally mounted on said support shelves of said vertical member, said telescopic members comprising a first member consisting of two hollow parallel spaced horizontal arms having depending pivot pins on the lower side of each horizontal arm in alignment with openings provided in the lower shelf of each pair of shelves and each of said pair of shelves being dimensionally related one to another so that said horizontal parallel arms with said depending pins may be freely slid into position so that said pins will drop into said openings, but such that said horizontal parallel arms will be restrained from movement in the vertical direction when they are pivoted into their operable position for securing said aperture, and said two hollow parallel spaced arms being connected by a multiple number of vertically disposed grid arms sufficient in number to bar ready passage through said aper-

- ture; and a second member which telescopes into said first member consisting of two similarly spaced and parallel spaced horizontal arms connected together at the far end with a vertical grid arm having an aperture therein;
- c. a second vertically disposed rigid member securely fastened to the other vertical jamb of said aperture and having a horizontally disposed element which engages said aperture in said vertical grid arm of said telescoping member when said telescoping member is opened to the full width of said aperture;
- d. and locking means for securing said engaged members.
2. The combination of claim 1 wherein said locking means is a key lock.
3. The combination of claim 2 wherein said rigid members are made of aluminum.
4. The combination of claim 3 wherein said device is mounted in such a manner that it pivotally swings into the interior of the building in which said aperture is located.
5. The combination of claim 3 wherein said device is mounted in such a manner that it pivotally swings away from the building in which said aperture is located.
